(57) **CLAIM**

The ornamental design for a closure, as shown and described.

DESCRIPTION

FIG. 1 is a front isometric view showing our new design of a closure;

FIG. 2 is a top plan view thereof;

FIG. 3 is a front elevational view thereof;

FIG. 4 is a rear elevational view thereof;

FIG. 5 is a left side elevational view thereof; and,

FIG. 6 is a right side elevational view thereof.

The broken line showing of a hinge is for illustrative purposes only and forms no part of the claimed design.

A central disk in the top of the closure lid is depicted with a contrast in surface shading relative to a peripheral portion of the closure lid and relative to the closure base, and such depiction represents a contrast in appearance via material, texture, or color so that the aesthetic appearance is enhanced.
